UNITED STATES PATENT OFFICE.

RICHARD W. OSWALD, OF PITTSBURG, PENNSYLVANIA.

TRUCK.

No. 899,797

Specification of Letters Patent.

Patented Sept. 29, 1908.

Application filed August 16, 1906. Serial No. 330,912.

To all whom it may concern:

Be it known that I, RICHARD W. OSWALD, a citizen of the United States of America, residing at Pittsburg, in the county of Allegheny and State of Pennsylvania, have invented certain new and useful Improvements in Trucks, of which the following is a specification, reference being had therein to the accompanying drawing.

10 This invention relates to trucks, and the invention relates to certain new and useful improvements in the side frames thereof.

The invention aims to provide positive and reliable means for strengthening and increasing the durable qualities of the frame, so, also for equalizing the stresses and strains exerted upon the frames by the road bed and weight of the rolling stock.

To this end, I have devised a novel cast 20 steel frame for trucks in which trusses are employed and advantageously distributed to insure a strong, inexpensive and highly efficient truck frame.

The detail construction of my improved 25 truck frame will be presently described, illustrated and then specifically pointed out in the appended claims.

Referring to the drawing forming part of this specification, like numerals of reference 30 designate corresponding parts throughout the several views, in which:—

Figure 1 is an elevation of a truck equipped with one of my improved frames, Fig. 2 is a plan of the frame, Fig. 3 is an elevation of a 35 truck equipped with a modified form of frame, Fig. 4 is a plan of the frame. Figs. 5 and 6 are elevations of trucks having frames of varying constructions, but within the scope of the invention.

40 To put my invention into practice, I construct my improved truck frames of cast steel, each frame consisting of an upper arch bar or compression member 1, and lower arch bar or tension member or pedestal tie 2, 45 which are connected together by vertically disposed bars 3 and flanged trusses 4. The ends of the bars 1 and 2 merge into the pedestal opening in which to support the journal boxes 5 of a truck. Between the central- 50 most bars 3 are supported spring planks 6 and transoms 7, and upon the planks 6 are mounted a nest of coiled springs 8 adapted to support the bolster 9 of a truck.

As shown, each of the flange trusses 47 consists of two reversely-disposed diagonally-extending braces formed integral with each

other and having their planes crossing each other at an angle and at a point intermediate the ends of the braces to form a shock-distributing point. This construction provides 60 a plurality of angles on opposite sides of the shock-distributing point being of equal degree, so that all strains placed on the truss are distributed from a common point and thereby preventing any liability of the truck 65 frame being disturbed in use.

The truck 10 illustrated in Fig. 1 is the most commonly used, and in connection with this type of truck I reinforce the upper arch bar 1 as at 11, also the bars 3, as at 12. 70

In Fig. 3 I have illustrated the pedestal jaws 14 and arch bar 1 as being reinforced, as at 15. In Fig. 5 a truck is illustrated especially designed for low bolsters.

A modification of the trusses is shown in 75 Fig. 6 wherein the flanged trusses are provided with central reinforcing webs 16, which tend to increase the rigidity of the frames. In this form the shock-distributing point is in the form of an annular member (annular 80 with respect to the actual crossing point of the construction shown in the other figures.) The effect, however, of this construction is practically the same as that above described.

Throughout the several forms of frames, it 85 will be observed that the trusses 4 form an important adjunct to the frames, and the many advantages of the frames over those at present used will be readily apparent to those skilled in rolling stock construction. 90

Such changes in the arrangement of the trusses and minor details of my improved frames as are permissible by the appended claims, may be resorted to without departing from the spirit and scope of the invention. 95

What I claim and desire to secure by Letters Patent, is:—

1. A truck side frame comprising a compression member and a tension member 100 spaced from and opposing each other, the space between said members being connected by parallel vertically-extending bars formed integral with said members, a bolster opening being formed between the inner bars, the adjacent openings having two reversely-disposed diagonally-extending braces formed integral with each other and having their planes crossing each other at an angle at a point intermediate the ends of the braces to 110 form a shock-distributing point, each of said braces having a reinforcing web extending on

opposite sides thereof, said braces and webs being formed integral with said members and said bars, said frame having pedestal openings at its ends.

5 2. A truck side frame comprising a compression member and a tension member spaced from and opposing each other, the space between said members being connected by parallel vertically-extending bars formed 10 integral with said members, a bolster opening being formed between the inner bars, the adjacent openings having two reversely-disposed diagonally extending braces formed integral with each other and having their 15 planes crossing each other at an angle at a point intermediate the ends of the braces to form a shock-distributing point, said point being in the form of an annular member, each of said braces having a reinforcing web extending on opposite sides thereof, said braces and webs being formed integral with said members and said bars, said frame having pedestal openings at its ends.

3. A truck side frame comprising a compression member and a tension member spaced from and opposing each other, the space between said members being connected 25

by parallel vertically-extending bars formed integral with said members, a bolster opening being formed between the inner bars, the adjacent openings having two reversely-disposed diagonally extending braces formed integral with each other and having their planes crossing each other at an angle at a point intermediate the ends of the braces to 30 form a shock-distributing point, said point being in the form of an annular member, said member having its periphery curved and formed integral with the bars, the latter radiating from said annular member, each of 35 said braces and the annular member having a reinforcing web extending on opposite sides thereof, said braces and their webs being formed integral with said members and said bars, the webs on the outer face of the 40 annular member being formed integral with the webs of the braces, said frame having pedestal openings at its ends.

In testimony whereof I affix my signature in the presence of two witnesses.

RICHARD W. OSWALD.
